CLAIM

The ornamental design for a faucet, as shown and described.

DESCRIPTION

In a preferred embodiment, the nature of this product is as a plumbing fixture in the form of a spray faucet primarily useful for washing various objects.

FIG. 1 is a left, top, front perspective view of a faucet embodying my new design;

FIG. 2 is a left side elevational view thereof;

FIG. 3 is a front elevational view thereof;

FIG. 4 is a right side elevational view thereof;

FIG. 5 is a rear elevational view thereof;

FIG. 6 is a top plan view thereof;

FIG. 7 is a bottom plan view thereof; and,

FIG. 8 is a front elevational view of a second embodiment, the right side elevational view thereof being a mirror image of that shown in FIG. 2, the left side elevational view thereof being a mirror image of that shown in FIG. 4, the rear elevational view thereof being a mirror image of that shown in FIG. 5, the top plan view thereof being a mirror image of that shown in FIG. 6, and the bottom plan view thereof being a mirror image of that shown in FIG. 7.

The broken line representations of an escutcheon in FIGS. 1-6 and 8, of outlet structures in FIGS. 2-4, 7, and 8, of mounting structure in FIG. 7, and of a handle/escutcheon in FIGS. 1 and 3-8, are for the purpose of illustration only, and form no part of the claimed design.
